US0D1085118S

(12) United States Design Patent (10) Patent No.: US D1,085,118 S
 Chen et al. (45) Date of Patent:  Jul. 22, 2025

(54) DISPLAY SCREEN OR PORTION THEREOF WITH GRAPHICAL USER INTERFACE

(71) Applicant: KDAN MOBILE SOFTWARE LTD., Tainan (TW)

(72) Inventors: Yu-Wen Chen, Miaoli County (TW); Chia-Ting Lee, Taichung (TW); Wen-Wei Lin, Kaohsiung (TW); Kai-Lin Shih, Tainan (TW); Ching-Yi Chiang, Tainan (TW)

(73) Assignee: KDAN MOBILE SOFTWARE LTD., Tainan (TW)

() Term: 15 Years

(21) Appl. No.: 29/887,616

(22) Filed: Mar. 23, 2023

(30) Foreign Application Priority Data

Sep. 23, 2022 (TW) 111304797

(51) LOC (15) Cl. 14-04

(52) U.S. Cl.

USPC D14/485

(58) Field of Classification Search

USPC D14/485-495

See application file for complete search history.

(57) CLAIM

The ornamental design for a display screen or portion thereof with graphical user interface as shown and described.

DESCRIPTION

The dot-dash broken lines illustrate a display screen or portion thereof and form no part of the claimed design. The dashed broken lines illustrate portions of the graphical user interface that form no part of the claimed design.

1 Claim, 1 Drawing Sheet
